Des No 1904

Charles Deans, of New York, N.Y.

ass to

Archer and Pancoast, of the same place.

Letters Patent No 1904-Dated March 1st 1864

Design for a jacket for Lamp Burners.

The schedule referred to in these Letters Patent and making part of the same.

in all whom it may concern:

Be it known that I, Charles Deans, of the City, County, and State of New York, have invented or produced a new and original Design for a jacket for Lamp Burners, and I do hereby declare that the following is a full, clear, and exact description of the same, reference being had to the accompanying drawings, making a part of this specification, in which-

Figure 1, is a side view of the lamp burner provided with a jacket of my design.

Figure 2, is a plan or top view of the same.

Figure 3, a side view of the same showing one edge or narrow side of the jacket.

Similar letters of reference indicate corresponding parts in the several figures.

This invention relates to a new and original design for a jacket for lamp burners such as are commonly termed coal oil burners.

A represents the cap of the burner which screws into the top of the fountain or body of the lamp, and B is the wick tube. These parts are of the ordinary shape and construction, and therefore do not form any part of the design.

B' is the jacket to which my invention or design pertains, a, a, are the standards of the jacket each of which is fluted vertically so as to leave ribs or beads a', a', a' extending their whole length or height and b, is the body of the jacket which encompasses the upper part of the wick tube and is of oblong form, slightly rounded in convex form at its upper edge, c, and rounded at its ends, d, and made of flaring form so as to be broader at its bottom than at its top.

2 Des No 1904

Des 1904

The beads a of the standards, a, extend upward on the rounded ends a of the jacket B to their top and at each side of the body b of the jacket there is a raised ornament formed of a bead c of D-shape, as shown clearly in figure 1.

Having thus described my invention, what I claim as new and desire to secure by Letters Patent, is—

The beads a on the standards a and ends of the body b of the jacket B, with the ornament composed of the bead c at the sides of the body of the jacket, to form a new and original design for a jacket for Lamp Burners, as set forth.
